UNITED STATES PATENT OFFICE

2,439,664

GLASS-LINED METAL SHELF WALL CLOSET

Adolph Marchand, Jackson Heights, N. Y.

Application January 27, 1945, Serial No. 574,924

3 Claims. (Cl. 312—112)

1

The object of the present invention is to provide a cabinet adapted as a wall inset; particularly applicable to bath and dressing rooms but useful generally, its characteristics being the combination of glass and metal elements to provide a composite structure in which the metal elements are substantially concealed, the inner walls and front edging of a metal box-like carrier being faced by unitary glass member which may hold shelves of glass for adjustment to various positions.

The invention will be described with reference to the accompanying drawings, in which:

Fig. 1 is a perspective view showing an embodiment of the invention, with the door opened.

Fig. 2 is a front elevation.

Fig. 3 is a side elevation.

Fig. 4. is an elevation, partly broken away showing the cabinet rearwardly of the door, the door connections being shown in sections.

Fig. 5 is a horizontal section on the line 5—5 Fig. 4.

Fig. 6 is a vertical section on the line 6—6 Fig. 1.

Fig. 7 is a vertical section on the line 7—7 Fig. 1.

Fig. 8 is a perspective view of the metal box-like member.

Fig. 9 is an enlarged fragmentary view, in section, taken immediately above one of the door connections when the door is open.

Fig. 10 is a sectional view similar to Fig. 9 showing the door closed.

Fig. 11 is a fragmentary vertical section showing the application of the door cushioning device.

Fig. 12 is an isometric view showing the door cushion.

Referring to the drawings and particularly Fig. 8, there will be inset into a wall, in one application of the device, a metallic box-like member. This member at its top and bottom will be cut and outwardly flanged to form the upper flange 2 and lower flange 3. This member is also provided with a laterally protruding tongue 3x which extends at right angles from one of its side-walls.

Adapted to be received within box 1 is a hollow glass structure comprising a back wall 4, side walls 5, and a rectangular flange 6.

The upper and lower sections of the flange 6 are, at one end thereof, cut away to receive shallow box-like securing members which are flanged to lie over upon areas of the glass flange 6. These box-like holding members are indicated at 7.

2

Each member 7 is formed with a plurality of apertures to receive screws 8, and these screws pass thru apertures in the metal box flanges 2, or 3, as the case may be. If desired, the members 7 may directly contact with said flanges 2, 3. In the present embodiment, however, washers 9 are interposed between two said members, and the screws are of sufficient length to pass thru a small tie-plate 10, and into the wall W.

10 Each box-like holding member 7 has pivoted thereto a hinge member 11, the latter having an area bent at right angles as indicated at 11x, this area being screwed, riveted, or welded, to a metallic door member 12.

15 The door member 12 is provided with a rectangular peripheral flange into which may be seated a glass facing 13 which may be spaced from the major wall of member 12 by suitable spacing channel members 13x (Fig. 9). Co-acting with the hinge member is a pivot hinge arrangement consisting of the links 14, 14x, the first link being pivoted to member 7 and the second being pivoted to hinge 11. At their points of pivotal connection each member 14, 14x, will be 20 provided with stops 15, so that when the door is in open position as shown in Fig. 13, members 14, 14x will not lie in straight-line or straightened toggle arrangement, which would impede the 25 closing of the door.

30 The angularly bent area 11x of hinge 11, is, at its end, bent again at right angles thus forming a spear head 11xx, so as to serve as a male latch member. This applies to the structure at both the top and the bottom of the door. For coaction 35 with the latch members 11xx there is positioned within each of the members 7 a U-shaped spring catch as indicated at 16 having the ends of its legs bent in round formation. Thus, when the door is closed, members 11xx will move aside the 40 springy legs of members 16 and the latter will contract as the heads of the members 11xx move inwardly a given distance, at which time the door will be in closing position. The door will thus be held closed and at the same time may be opened 45 by moderate pull.

An additional holding means for the glass member of the cabinet is preferably provided. It makes use of tongue 3x carried by the metallic box-like member, the tongue being apertured to 50 receive a screw 18 which passes thru a soft washer 19, thence thru an opening in glass flange 6, and into or thru metallic tongue 3x. The screw may be of sufficient length to enter the wall W, if desired.

55 The sides of the glass member which affords

the immediate containing member of the cabinet will be formed with spaced channelway to receive shelves, as shown particularly in Figs. 1 and 4 of the drawing.

In the position of the members as illustrated in Fig. 1, the glass cabinet structure has not been brought into final abutting relationship with the box-like metal member 1, and is shown somewhat spaced from the latter for clarity of illustration. When the screws 8 and filler plate 10 are applied and the screws 8 and 18 are tightened, a close fitting assembly will be provided. As hereinbefore stated washers 9 may be interposed between flange 2 and member 7.

It will be understood that various modifications may be made in the form and arrangement of the elements illustrated without departing from the spirit of the invention.

I claim:

1. A cabinet for bathrooms and the like, comprising a member having upper and lower walls and sidewalls and being adapted to be set in a wall with its front edge substantially flush with the wall, said member having spaced flanges apertured to receive fastening elements, a unitary glass member disposed in said wall-inset member and having upper and lower walls and sidewalls and a flange around its entire frontal periphery adapted to abut and conceal the edge of the wall-inset member, a pair of box-like holding members fitted in apertures formed in the flange of the glass member, said holding members having a plurality of apertures and having angular lateral flanges overlapping the said flange of the glass member, and fastening members extending through the said apertures of the box-like members and through the spaced flanges of the wall-inset member so as to lock the glass member to the wall-inset member.

2. A cabinet for bathrooms and the like comprising a wall-inset member having spaced flanges apertured to receive fastening elements, a unitary glass member having upper and lower walls and side walls, said glass member having a surrounding flange adapted to abut and conceal the edge of the wall-inset member, a pair of box-like holding members fitted in apertures formed

in the flange areas of the glass member and having face abutments for said flange, fastening members for securing said box-like holding members to the flanges of the wall-inset member

5 whereby the glass member is locked to the wall-inset member, in combination with a door, a glass facing carried by the door, and hinged members carried by the box-like holding members consisting of two links pivotally connected, one to the box-like member and the other to the door, and a pivoted connection between them, said first link swinging inside the box-like member and said latter link folding upon the said first link.

3. A cabinet for bathrooms and the like comprising a wall-inset member having spaced flanges apertured to receive fastening elements, a unitary glass member having upper and lower walls and side walls, said glass member having a surrounding flange adapted to abut and conceal the edge of the wall-inset member, a pair of box-like holding members fitted in apertures formed in the flange areas of the glass member and having face abutments for said flange, fastening members for securing said box-like holding members to the flanges of the wall-inset member

10 whereby the glass member is locked to the wall-inset member, in combination with a laterally protruding tongue carried by the wall-inset member at one side thereof, a door, hinge means carried by the box-like holding members and connected to the door at a side thereof opposite the said protruding tongue of the wall-inset member, a door cushion, and a screw device passing thru such cushion, thru the flange of the glass member and secured to the said protruding tongue of the wall-inset member.

ADOLPH MARCHAND.
